FOUNDATION GARMENT SUPPORT STRUCTURE

Minna R. Schubert, Saginaw, Mich., assignor to Le Monde Corset Company, Saginaw, Mich., a corporation of Michigan

Application February 10, 1954, Serial No. 409,369

2 Claims. (Cl. 2-37)

The present invention relates to a new and unique foundation garment structure and more particularly to supporting means incorporated into foundation garments of the full length corset type.

Two problems have long confronted the industry: (1) maintaining adequate support to model a random figure into a fashionable torso contour while maintaining comfort to the wearer of the garment with lightness of weight, (2) preventing the structural details of the garment from appearing exteriorly and preventing an excessive flesh bulge in terminal areas of support.

The availability of modern fabrics and modern elastic mesh material has made possible an overall reduction in garment weight and comfort, but in garments where more support is necessary than is available in combinations of elastic mesh material and fabric the difficulty of achieving minimum weight, and comfort, while providing adequate support has resulted in an emphasis upon contouring the structural support members in such a manner as to prevent visible exterior contour variations where the additional support is applied, and to contain gracefully as a contour progression the bulging usual around the upper periphery of such garments.

It is therefore an object of the present invention to present a new and novel means for support panels and sections in foundation garments.

It is another object of this invention to present a foundation garment structure which is comfortable to the wearer while achieving maximum body contour support.

Still another object of this invention is to provide a combination of foundation garment panels capable of controlling the bulge normal in garments of this type around the periphery thereof.

Other objects and inventive characteristics of this new and unique foundation garment structure will become increasingly apparent to those familiar in the art as the description proceeds.

In the drawing:

Figure 1 is a front elevation in phantom line indicating conventional flesh bulges about the terminal portions of a full length foundation garment.

Figure 2 is a front elevation of a modeled garment with one front section exploded to illustrate the construction and extent of the stay-carrying floating liner.

Figure 3 is a side elevation showing the elastic panel upon the wearer terminating somewhat above the waist.

Figure 4 is a fragmental side elevation of the same modeled garment with the elastic panel partially cut away to reveal the bias cut of the inelastic liner in fully extended position.

Figure 5 is a fragmental side elevation of the same garment but not upon a figure showing the inelastic panel liner back of the elastic side panel in a relaxed or inoperative position.

Figure 6 is a rear elevation of a modeled garment partially cut away to reveal the position of the floating liner

2

with stays behind the rear inelastic section. In the cut-away portion stays are shown adjacent the stitching margin illustrating a conventional non-floating insertion of stays.

5 Referring more particularly to the drawing a full length foundation garment is illustrated comprised of front vertical sections 11 and 11a, front panels 12 and 12a and back panels 13 and 13a. Elastic side panels 14 and 14a are provided. A brassiere top 15 of the uplift type is 10 illustrated as attached to the top of the garment and supported by conventional shoulder straps 16. Rear strap support sections 17 and 17a provide upper extensions of the back panels 13 and 13a respectively.

The vertical elastic panels 14 and 14a are placed symmetrically running down either side of the garment. Adjacent to the elastic panels 14 and 14a and rearwardly positioned with respect thereto are inflexible support panels 13 and 13a and their respective strap support sections 17 and 17a stitched securely to the rear vertical edge of the elastic panels 14 and 14a. Inwardly from said inflexible panels 17 and 17a and coincidentally in position behind said inflexible panels 17 and 17a is a stay liner 18 (Fig. 6). A plurality of stays 19 and 20 are stitched into said stay liner 18 running substantially 25 the length of the garment. A similar arrangement is repeated behind the panel 13a and support extension 17a. By reason of the cutaway section 17 the floating liner 18 is best illustrated in Fig. 6.

At the top of the elastic panels 14 and 14a are provided (Fig. 4) "bias-cut" liners 21 and 21a secured longitudinally to the edges of the adjacent inflexible panels 12 and 12a and 13 and 13a and containing sufficient material laterally to stretch taut across the top of said elastic strips 14 and 14a only as the elastic strips 14 and 14a 30 approach the limit of their stretch. ("Bias-cut" as used herein means a tapered cut across the top edge of the fabric and has no reference to a bias cut with respect to the strand direction of the fabric).

Abdominal support sections 11 and 11a on either side 40 of the opening means 22 also require stay support. Stay liners 23 (as shown behind the cutaway section 11a in Fig. 2) are provided which correspond in contour to the outer inelastic sections 11 and 11a. As in the rear stay liners 18 vertically oriented stays 24 are stitched 45 into the liners 23 and extend substantially lengthwise of the abdomen for support. Hose supporters 25 are attached to the lower edge of the liners 23 and loop outwardly to attach to the lower seam 26 of the sections 11 and 11a. The materials comprising both liners 18 and 23 and panels 11 and 11a and 13 and 13a are inflexible fabrics. The lowermost extension of the liner 23 generally parallels the seams of the panels 11 and 11a nearest the vertical zipper closure 22 illustrated. Hose supporting members 25 are then securely stitched to the 50 bottom of the liner extensions 27 and the bound edge 26 of the bottom of the panels 11 and 11a.

Other hose supporting members 28 are arranged conveniently about the lower peripheral edge of the garment and stitched thereto in the conventional manner but are 55 looped to attach to the lower edge of the garment.

The stay liners 18 and abdominal stay liners 23 are divorced from attachment to the outer panels except in the vertical seams. The back stays 19 and 20 and the abdominal support stays 24 are not in any way attached 60 to the fabric of the corresponding panels. In this manner the stays appropriately are positioned from vertical or lateral displacement and any flesh ridges caused by the action of the stays is suppressed by the buttressing action of the inelastic outer panel. In addition, the liners 65 are free floating independently of the outer fabric panel and cannot damage the fabric of the outer panel or cause 70 discomfort to the wearer.

The hose supports 25 attached to both the bottom of the panels 11 and 11a and to the liner extensions 23 act to tensionally assist the support of the liners and simultaneously the panels.

As in conventional foundation garments the vertical elastic strips 14 and 14a upon either side of the garment provides the tensioning means of support that is non-re-siliently transmitted through the inelastic panel members to give the desired support to the garment. Unlike conventional garments, however, beyond the top of the elastic strip a limited expansion section 21 extends upwardly to termination in the upper peripheral binding 29. The lower portion of the limited expansion section 21 is attached to only the vertical seams 30 of the elastic strips 14 and 14a and is provided with a built-in excess of inelastic material to achieve tautness behind and above the elastic strips 14 and 14a only when the elastic members 14 and 14a approach the limit of their elasticity. In this manner there is achieved a compaction of flesh as it commences to roll over the upper edge of the elastic panel members 14 and 14a and the flesh bulge is thus merged into the contours the garment seeks to model. In Fig. 1 a phantom line presentation indicates a somewhat exaggerated flesh bulge under the arms of the wearer resulting from a garment not provided with limited expansion sections 21 extending above the elastic panels 14 and 14a. By reference to Fig. 5 it will be seen that the expansion section 21 is provided with a lateral excess of material behind the relaxed elastic panel 14a. In Fig. 4 the elastic panel 14a is cut away to show the bias-cut lower edge 31 of the expansion section 21. By reason of the bias-cut behind the elastic panel 14a supporting stresses are added to the garment when the inelastic expansion section 21 becomes taut and no waist bulges are occasioned by reason of the expansion section 21 behind the elastic panel 14a. Shoulder straps 16 are arranged to vertically suspend the garment from the shoulders of the wearer and the back sections 17 and 17a are suspended from the shoulder straps 16 to achieve maximum flesh compaction above the limits of the back stays 19 and 20.

The vertical panelling arrangement permits vast experimentation in contour modeling and the novel structure incorporating stay support which floats against the panel material makes possible minimum discomfort to the wearer with maximum control of contours.

It is, of course, understood that while the description has proceeded to describe liner type panels and sections on one side of the garment, they are intended to be repeated symmetrically behind the corresponding opposite panel or section of the garment. It will also be understood that the construction illustrated may be shifted to other sections and panels of a similar garment.

Having thus described the invention it will be appreci-

ated that a significant advancement has been made in the foundation garment art by the use of liners for buttressing support while maintaining lightness without sacrifice in producing fashionable torso contours.

I claim:

1. In a body encircling foundation garment structure the combination including: a plurality of elastic panels running vertically the length of said garment; non-elastic vertical panels joined to said elastic panels at the vertical edges thereof and forming a tubular sheath therewith; and a partial inner liner backing said elastic panels and having a bias cut lower edge extending substantially below the upper terminal edge of said elastic panels and fastened to the vertical edges of said panels at the jointure between said elastic and non-elastic panels, and being laterally coextensive with said elastic panels when said elastic panels approach full expansion to provide inflexible pressure-distributing support as said elastic panel approaches the limit of its elasticity in the upper terminal area.
2. In a body encasing foundation garment comprised of joined vertically oriented panels and front and back sections, the combination including: oppositely and symmetrically positioned selected panels of substantially non-elastic material; pocketed inner liners of substantially non-elastic material substantially similar in size to said selected panels and secured to said selected panels at the vertical edges thereof; a plurality of ribs running substantially the length of said panels and stitched against vertical or lateral displacement into the pockets of said inner liners; vertical elastic panels adjacent said non-elastic panels and forming expansion units at the sides of said garment and being stitched to said non-elastic panels and said liners on one side and to another vertical non-elastic panel on the other side; and partial non-elastic liners having an upper edge substantially above the upper terminal edge of said elastic panels, and having a bias-cut bottom edge substantially below the upper terminal edge of said elastic panels, attached to the vertical edges of adjacent panels, and partially backing said elastic panels, and being laterally coextensive with said elastic panels when said elastic panels approach full expansion to provide inflexible pressure-distributing support as said elastic panel approaches the limit of its elasticity in the upper terminal area.
